Atty.

UNITED STATES PATENT OFFICE.

SHERMAN P. COOLEY, OF NEW BRITAIN, CONNECTICUT.

ATTACHING KNOBS TO THEIR SHANKS.

SPECIFICATION forming part of Letters Patent No. 439,120, dated October 28, 1890.

Application filed September 9, 1890. Serial No. 364,403. (No model.)

To all whom it may concern:

Be it known that I, SHERMAN P. COOLEY, a citizen of the United States, residing at New Britain, in the county of Hartford and State 5 of Connecticut, have invented certain new and useful Improvements in Attaching Knobs to their Shanks, of which the following is a specification.

My invention relates to improvements in 10 attaching knobs to their shanks, and the chief object of my improvement is to produce a more substantial article.

In the accompanying drawings, Figure 1 is a central longitudinal section of a knob-shank 15 and knob. Fig. 2 is a longitudinal section of the knob-shank on a plane at right angles to that shown in Fig. 1. Fig. 3 is a side elevation of said knob-shank with a corner elevation of the attached butt. Fig. 4 is a detached side elevation of the wrought butt for 20 my knob-shank. Fig. 5 is a side elevation of another ordinary form of knob-shank with a corner elevation of my butt attached thereto; and Fig. 6 is a perspective view of a butt for 25 my knob-shank, provided with notched or serrated edges.

A designates a knob-shank of ordinary form and having the ordinary squared socket 30 7 for the knob-spindle, and B is the knob secured thereto by means of a wrought-metal butt 8 and surrounding soft metal 9. Ordinarily knobs are attached to their shanks by inserting their butts in a hole in the knob and filling the hole with soft metal; but ordinarily the butt inserted in said hole has 35 been formed of cast metal integral with the knob-shank.

Instead of the ordinary cast-metal butt I employ a wrought-metal butt 8, the same being formed principally of two legs affixed to the body of the shank during the casting process and forming a continuation of the sides of the socket 7 for the knob-spindle. I prefer to form this shank of a single piece of 45 sheet metal bent into loop form, as shown, and to provide its inner end with enlargements or projections 10 for being inclosed by the metal forming the shank, as indicated by the broken lines in Fig. 1. It may, however, 50 be formed of either flattened or round wire bent into loop form, and it is obvious that

the projections or enlargements at the inner end for being embedded in the cast-metal shank may be of various forms. If desired, when formed of sheet metal the projecting 55 portion of the butt may be notched or recessed on its edges, as shown at 11, Fig. 6, and, if desired, the connection between the two legs at the outer end of the butt 8 may be omitted.

A wrought-metal butt formed as described 60 may be attached to a sand core for forming the spindle-socket 7 in the knob-shank and with the core set within the core-print in the ordinary manner of casting, so that when the knob-shank A is cast it will inclose the end 65 of said butt, as shown, and firmly secure it to the knob-shank. Tumbling in a rolling barrel will remove the sand core and leave the knob-shank and attached butt in the form represented in Figs. 2, 3, and 5. This shank 70 is placed on the knob B, with the wrought-metal butt in a hole in said knob and the remaining space filled with lead or soft metal 9, as shown in Fig. 1.

By making the butt 8 of wrought metal, 75 with its legs forming a continuation of the sides of the hole through the shank, I am enabled to employ a sand core in casting the shank, and thereby produce the knob-shank and butt at a nominal price. The butt, although small, is of superior strength and not likely to be broken off or become detached. It is smaller than the ordinary cast-metal butt, so that the hole in the knob may be smaller, thereby greatly increasing the strength and 85 durability of the knob.

I claim as my invention—

1. The herein-described knob and shank attachment, consisting of the cast-metal knob-shank and the wrought-metal butt secured 90 thereto for attaching to the knob with soft metal, substantially as described, and for the purpose specified.

2. In a knob attachment, a cast-metal knob-shank and a separately-formed butt having 95 two legs which form a continuation of two sides of the spindle-socket, substantially as described, and for the purpose specified.

SHERMAN P. COOLEY.
